UNITED STATES PATENT OFFICE.

NATHAN SADOVSKY, OF SAN ANTONIO, TEXAS.

PRINTING-PRESS.

1,088,732.

Specification of Letters Patent: Patented Mar. 3, 1914.

Application filed January 21, 1913. Serial No. 743,413.

To all whom it may concern:

Be it known that I, NATHAN SADOVSKY, a citizen of the United States, residing at San Antonio, in the county of Bexar and State of Texas, have invented a new and useful Printing-Press, of which the following is a specification.

The present invention relates to improvements in printing presses, the primary object of the invention being the provision of a printing press, in which the type carrying member is a circular rotary disk and has adjustably connected with relation thereto, diametrically disposed ink supplying rolls and paper carrying platens, the paper carrying platens being frusto-conical members provided with paper clamps, whereby the paper is properly gripped thereon and delivered to the type carried by the printing bed to be released at the proper instant and before the type passes below the inking rolls.

A further object of the present invention is the provision of a novel mechanism for elevating the ink supplying rolls and paper carrying platens to permit of the passage of the type therebelow without being affected.

With the foregoing and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed without departing from the spirit of the invention.

In the drawings--Figure 1 is a view in elevation of the complete press. Fig. 2 is a top plan view of the complete press, a portion of the rotary bed being broken away. Fig. 3 is a cross section taken on line 3--3 of Fig. 2. Fig. 4 is a detail perspective view of the roller or shaft for manually elevating the paper carrying platens and ink rolls. Figs. 5 and 6 are detail views of the sleeve or tubular shaft constituting the adjustable member of the automatic device for elevating the inking rolls and paper carrying platens.

Referring to the drawings, the numeral 1 designates the base of the framework which is provided with the four upstanding posts 2--2 and 4--4 and the center pedestal 3. Carried by the upper end 6 of the pedestal

way 8 for the anti-frictional balls 8', which form an anti-frictional support for the rotary type carrying platen or bed 9. This rotary platen 9 is provided with the large bevel gear 10, which is in mesh at all times 60 with the bevel gears 11 carried by the four shafts 12, each shaft 12 having a small gear 13 in mesh at all times with the intermediate gear 14, and thereby, as all of the shafts 12 are rotated simultaneously through any 65 known medium, as for instance the motor M, Fig. 1, the gears 15 and the tubular shafts 16 will be rotated. Each shaft 16 is constructed, as clearly shown in Figs. 3 and 6 and has mounted upon each end 19 70 thereof, the four radially disposed eccentrics or cams 17.

Mounted for sliding movement, one to each of the respective posts 2 and 4, are the sliding plates 20--20', there being two of 75 each, while mounted in the upper portion 6 of the pedestal 3 and also vertically movable, are the inner posts 21--21', there being two of each of these. Both of the plates 20--21 are disposed in pairs to carry the 80 respective paper carrying frusto-conical platen rollers 28. The other plates 20'--21' are disposed in pairs and carry the inking rollers 29.

As clearly shown, the journals 27 of the 85 respective platens 28 are mounted in the upper ends of the respective plates 20 and 21, and as the rotation of the shafts 16 is timed relatively to the movement of the type below the respective paper carrying 90 platens 28, the two plates 20--21, due to the engagement of either one of the cams 17, will be elevated in timed relation with the rotary platen 9, such timed relation depending upon the position of the respective sliding shafts 16, and as to which of the cams 17 are disposed below the projections 20a 95 of the plates 20--21.

The gears 9' and 28' provide a means whereby the bed 9 transmits rotation to the 100 platens 28.

As clearly shown in Fig. 3, the shafts 16 are slid or moved by means of the grooved collars 33 and the arms 34 so that the plates 20 and 21 will not be affected by the rotation of the shafts 16, it being simply necessary to place one of the cams 17 below the projection 20a to cause the platen to be elevated, and as these cams are disposed radially, the 105 timed movement of the elevation of the re- 110

spective platens 28 and ink rollers 29 may be changed at will according to the selection of the respective cams 17 to be placed into operation. The sliding of each shaft 16 is 5 accomplished by the manually operable feed screw 35, which is operably connected through the collar 34 to its respective arms 34.

Each platen 28, is provided with the paper 10 clamps 30 of usual structure, the same being disposed to grip the paper when fed to the roll by the operator at each side of the machine, or when fed automatically, the paper being automatically released after the impression 15 has been placed thereupon, and in the usual manner. By this means it is evident that the various paper carrying platens 28 and ink rolls 29 may be operated automatically to be elevated from the type carrying 20 platen 9, at the desired point, said type carrying platen 9 being provided with two type carrying faces which are disposed at diametrically opposite positions, so that the inking rollers will ink the type for the 25 presentation of the same below the succeeding paper carrying platen 28, thus permitting two inkings and two impressions at each rotation of the bed 9.

Each tubular shaft 16 is rotatably mounted 30 upon a cylindrical shaft 22, which is capable of an oscillatory movement, and has secured to each end the cam plate 23, there being two cam plates 23 to each shaft 22. These plates are mounted eccentrically or in 35 such a position as to be projected below the respective projections 20^b of the respective plates 20—21 and 20'—21', to elevate the respective pairs of plates and the platens 28 or ink rollers 29, these plates 23 constituting 40 a means for retaining the platens 28 and the inking rollers 29 above the bed of the rotary member 9, so that any one or pair of the respective platens 28 and ink rollers 29 may be rendered inoperative. To accomplish this 45 end, each shaft 22 has its individual actuating mechanism, which comprises a foot treadle 26, connected by a link 24 to the lever 25, whereby the depression of the foot treadle will operate the lever 25 which causes 50 the shaft 22 to be oscillated to place its respective plates 23 below the projection 20^b and thus elevate the selected pair of plates 20—21 or 20'—21'.

The platen and inking rollers are inter- 55 mittently raised and lowered relatively to the rotating bed 9, so that they will contact only the type carrying platens thereof, said portions not occupying the full area of the bed. Thus the platen and inking rollers, 60 respectively, are permitted to move toward and in engagement with the bed, only when the type are passing therebelow.

From the foregoing description, taken in connection with the drawings, it is evident 65 that a printing press made according to and

embodying the present invention, permits two operators to feed the paper to the same, although as before stated, the paper may be fed and moved from the press automatically.

It will be further noted that any means 70 may be provided for removing the paper from the type and carrying the same in a path tangential to the rotation of the type carrying bed 9, thus insuring the proper delivery of the finished material away from 75 the press.

What is claimed is:

1. In a printing press, a frame, a rotary circular type bed mounted thereon, a plurality of diametrically disposed impression 80 rollers, a plurality of diametrically disposed ink rollers, and manually adjustable automatically actuated means for moving the impression rollers and ink rollers to and from the bed and in varying timed relation 85 to the bed.

2. In a printing press, a frame, a rotary circular type bed mounted thereon, a plurality of diametrically disposed impression rollers, a plurality of diametrically disposed 90 ink rollers, automatically actuated means for moving the impression rollers and ink rollers to and from the bed and in timed relation to the bed, and manually controlled means for adjusting the actuating mechanism for actuating the rollers at varying times.

3. In a printing press, a frame, a rotary circular type bed mounted thereon, a plurality of diametrically disposed impression 100 rollers, a plurality of diametrically disposed ink rollers, manually adjustable automatically actuated means for moving the impression rollers and ink rollers to and from the bed and in varying timed relation to the 105 bed, and manually actuated means for elevating the rollers to maintain the same out of contact with the bed.

4. In a printing press, a base, a plurality of standards carried by the base, a horizontally disposed supporting plate carried by the standards, a rotary circular type bed mounted upon the plate, a plurality of diametrically disposed frusto-conical impression rollers, a plurality of diametrically disposed ink rollers, said ink rollers being disposed to alternate with the impression rollers, and adjustable means for automatically actuating the various rollers to move the same to and from the bed and in varying 120 timed relation to the bed.

5. In a printing press, a base, a plurality of standards carried by the base, a horizontally disposed supporting plate carried by the standards, a rotary circular type bed 125 mounted upon said plate, a plurality of diametrically disposed frusto-conical impression rollers, a plurality of diametrically disposed ink rollers, said ink rollers being disposed to alternate with the impression roll- 130

ers, adjustable means for automatically actuating the various rollers to move the same to and from the bed and in varying timed relation to the bed, and manually actuated means for elevating and maintaining the elevation of the rollers.

In testimony that I claim the foregoing as

my own, I have hereto affixed my signature in the presence of witnesses.

NATHAN SADOVSKY.
